CANDLE GLASS

Peter N. Reed, San Antonio, Tex., assignor to
Reed Candle Company, San Antonio, Tex.

Filed Feb. 2, 1972, Ser. No. 223,056

Term of patent 14 years

Int. Cl. D26—01; D26—05

U.S. Cl. D48—2

The figure is a side elevation view of a candle glass showing my new design.

The major section of the sidewall is generally cylindrical, but decreases in diameter as it extends upwardly. The pedestal is shown in broken lines for illustrative purpose only.

I claim:

The ornamental design for a candle glass, as shown and described.
